CONCRETE TIE ROD

John Novelo, 129-17 Rockaway Beach Blvd.,
Belle Harbor, N.Y.

Filed Feb. 9, 1959, Ser. No. 792,117

2 Claims. (Cl. 25-131)

This invention relates to the art of masonry and concrete construction and more particularly to a novel tie for use in conjunction with forms for poured concrete structures.

The primary object of the present invention resides in the provision of a concrete form tie provided with novel means for breaking off the ends of the tie so as to facilitate rapid release of the forms.

The invention features the use of novel fittings of cylindrical shape which are arranged on a tie for facilitating rotation of the ends thereof so as to enable the tie to be more easily twisted and broken, thereby permitting the release of forms and the elimination of the projecting ends of the ties.

Another object of the present invention resides in the provision of a concrete form tie that employs a novel arrangement for enabling a tool to be inserted in the end of the tie for twisting the end of the tie, which means may also serve to aid in holding a form in position.

Another feature of the invention resides in the provision of novel fittings which may be used and re-used in conjunction with wall ties in an convenient manner.

Still further objects and features of the present invention reside in the provision of a concrete form tie that is simple in construction, efficient in use, capable of being manufactured from readily available materials, and which is inexpensive to manufacture, thereby permitting wide use and distribution.

These, together with the various ancillary objects and features which will become apparent as the following description proceeds are attained by this concrete form tie, preferred embodiments being shown in the accompanying drawing by way of example only wherein:

Fig. 1 is a perspective view of a concrete form tie constructed in accordance with the concepts of the present invention with parts thereof being broken away;

Fig. 2 is a longitudinal sectional view of the concrete form tie comprising the present invention but showing two types of fittings which may be used in conjunction with the present invention;

Fig. 3 is a vertical sectional view taken along the transverse plane of line 3-3 in Fig. 1, illustrating particularly the construction of one of the fittings;

Fig. 4 is an elevational detail view illustrating the manner in which one of the fittings is positioned on the tie;

Fig. 5 is a transverse vertical sectional view as taken along the plane of line 5-5 in Fig. 2.

With continuing reference to the accompanying drawing wherein like reference numerals designate similar parts throughout the various views, reference numeral 10 generally designates the concrete form tie comprising the present invention which is constructed on an elongated strap or bar 12 of metal of suitable length to extend the distances between opposed forms and to extend a little bit therebeyond.

The bar 12 is provided with pairs of slots 14 and 16 therein, each of which pair of slots substantially reducing the effective cross sectional area of the bar 12 at the slots.

2

Punched or otherwise formed in the bar 12 are slits 18 and 20. The slits terminate short of the ends 22 and 24 of the bar and permit the bar to have upwardly extending ears 26 and 28 pressed or stamped, while opposite and downwardly extending ears 30 and 32 are suitably formed in the bar 12 so as to provide means for receiving a tool such as a screw driver, or other similar elongated member for use as a lever in a manner to be hereinafter defined.

Between the ears 26 and 30 and the slot 16 is a fitting 34, and another fitting 36 is disposed between the slots 14 and the ears 28 and 32. These fittings form cylindrical bearings for the bar 12.

As can be seen best in Figs. 2-4, one preferred form 15 of the fitting 36 is in the guise of a cylinder of synthetic plastic material, such as any suitable synthetic resin, polyethylene, preferably of an exceedingly smooth non-porous surface and being slightly compressible or elastic.

The cylinder is provided with a notch 38 of preferably 20 wedge shape extending diametrically almost the whole thickness of the cylinder, but terminating as at 40, whereby the cylinder can clampingly engage the bar 12, as can be best seen in Fig. 3, the bar being inserted in the notch 38, whereby the draw portion 42 and 44 formed by notch 34 will clampingly grip the bar. It is to be 25 recognized that this form of the invention enables the fitting 36 to be rapidly and easily placed on the bar.

Another form of the invention is shown in Figs. 2 and 30 5 wherein substantially semi-cylindrical members 46 and 48 are bonded by suitable adhesive layers 50 and 52 to the bar 12.

The semi-cylindrical members 46 and 48 are preferably 35 formed of cork which may have its outer surface treated to render it non-porous and relatively smooth. The cork is a highly desirable material for use in this invention in that it is somewhat compressible and elastic.

In use, the concrete tie 10 is employed between opposed 40 forms used in poured concrete constructions. The fittings 34 and 26 extend partially through the forms and partially into the space between the forms so that after the concrete has set, insertion of a tool in the respective openings between the ears 26, 30 and 28, 34, respectively, will enable the ends of the tie rod to be twisted and the bar broken at the notches 16 and 14, respectively.

The fittings 34 and 36 provide bearings for facilitating the twisting of the ends since they are circular in cross section in conjunction with the bar 12.

Further, upon removal of the ends of the tie rod and the forms, the cylinder bearings will leave readily visible 50 and highly desirable partial bores in the concrete wall, which may be easily grouted and filled with cementitious material, whereby no protruding tie wires or ties which can initiate a path for water through the foundations will be present.

55 Thus, it can be seen that there has been defined a concrete tie rod in the form of the elongated bar of substantially flat rectangular cross section with the bar having spaced pairs of opposed slots therein. The slots are spaced from the end of the bars and substantially reducing the cross sectional dimension of the bar at the slots. Fittings are secured on the bar to form cylindrical bearings for facilitating twisting the ends of the bar to break the bar at the slots, while ears are provided at the ends of the bar for facilitating the application of fuselage 60 on the bar.

Various changes and modifications may be made without departing from the spirit and scope of the present invention and it is intended that such obvious changes and modifications be embraced by the annexed claims.

70 Having thus described the invention, what is claimed as new and desired to be secured by Letters Patent, is:

1. A concrete tie rod comprising an elongated bar of

substantially flat rectangular cross section, said bar having spaced pairs of opposed slots therein spaced from the ends of said bar substantially reducing the cross sectional dimension of said bar at said slots, and fittings secured on said bar outwardly of said slots and forming cylindrical bearings for facilitating twisting of the ends of said bar to break said bar at said slots, each of said fittings being formed of a cylinder of a smooth, slightly compressible synthetic plastic material, said cylinder having a notch of wedge shape formed therein, said cylinder receiving said bar in said notch and clampingly engaged said bar.

2. A concrete tie rod comprising an elongated bar of substantially flat rectangular cross section, said bar having spaced pairs of opposed slots therein spaced from the ends of said bar substantially reducing the cross sectional dimension of said bar at said slots, and fittings secured on said bar outwardly of said slots and forming cylindrical bearings for facilitating twisting of the ends of said bar to break said bar at said slots, said bar having spaced 15 slits therein adjacent the respective ends of said bar, said

bar having ears integrally deformed at said slits from said bar for receiving a tool to apply leverage on the ends of said bar, each of said fittings being constructed of an exceedingly smooth, slightly compressible synthetic plastic material, each of said fittings being formed of a cylinder having a notch of wedge shape therein each of said cylinders receiving said bar in said notch and clampingly engaging said bar.
